(57) **CLAIM**

The ornamental design for an adapter base with ball mount, as shown and described.

DESCRIPTION

FIG. 1 is a solid perspective view showing my new design; FIG. 2 is a top front right side perspective view thereof; FIG. 3 is a top front left side perspective view thereof; FIG. 4 is a top rear right side perspective view thereof; FIG. 5 is a bottom perspective view thereof; FIG. 6 is a front elevational view thereof; FIG. 7 is a rear elevational view thereof; FIG. 8 is a left side elevational view thereof; FIG. 9 is a right side elevational view thereof; FIG. 10 is a top elevational view thereof; and, FIG. 11 is a bottom elevational view thereof. Portions of the ornamental design for an adapter base with ball mount of the invention that are not shown in the figures are disclaimed and form no part of the claimed design. The broken lines illustrate portions of the adapter base with ball mount and form no part of the claimed design.

1 Claim, 4 Drawing Sheets
